AMINO ALKOXY PHENYL METHANES

Robert E. Allen, Wyoming, and Frank P. Palopoli, Cincinnati, Ohio, Edward L. Schumann, Kalamazoo, and William C. Day, Lansing, Mich., and Vernon J. Feil, Cincinnati, Ohio, assignors to The Wm. S. Merrell Company

No Drawing. Application February 21, 1958
Serial No. 716,565

6 Claims. (Cl. 260—294.7)

Our invention relates to new chemical compounds which can be regarded as amino ethers of benzal- and benzyl carboheterocycles. They are distinguished, in general, by their anti-estrogenic activity in the endocrine system, anti-inflammatory activity, anti-gonadotrophic activity, activity in decreasing blood cholesterol levels, activity in thyroid conditions, activity in the respiratory system and anti-fungal activity. Some of the compounds possess various combinations of these properties.

As estrogen antagonists, the compounds are useful in the treatment of hyperestrogenism and disorders related to this condition, e.g., ovarian hyperfunction, endometriosis, Kleinfelter's syndrome, dysmenorrhea, amenorrhea, menopausal dysfunction, functional bleeding, sexual precocity and similar conditions. They are active both orally and parenterally and so can be administered by either route, though the oral route is preferred in most instances. Some of the compounds have a high degree of activity as estrogen antagonists and are also advantageously non-estrogenic. Some of the compounds with anti-estrogenic activity are also uterotrophic.

As anti-inflammatory agents, the compounds are useful in alleviating the symptoms of such collagen diseases as arthritis and rheumatism and in the topical treatment of inflammation. Some of the compounds possess the novel combination of anti-inflammatory and anti-estrogenic activities and are especially advantageous for this reason. They are useful topically, orally and parenterally for this purpose.

As blood cholesterol level depressants, the compounds are useful in the treatment of cardiovascular diseases such as atherosclerosis. They are useful orally for this purpose.

As gonadotrophic inhibition agents, the compounds are useful for the treatment of fertility and sterility problems and can be administered orally or parenterally for this purpose.

The compounds are also useful in treating respiratory diseases and are useful orally or intranasally for this purpose. Some of the respiratory infections that can be treated are common cold, influenza, sinusitis, whooping cough, adenovirus, and pneumonia of different etiologies.

The compounds are also useful in treating thyroid conditions as they exhibit activity in reducing thyroid weight. They are useful orally and parenterally for this purpose.

As anti-fungal agents, the compounds are useful in the topical treatment of fungus infections such as torulosis, ring worm, athlete's foot, blastomycosis, histoplasmosis, tinea capitis, and monila infections. They are also useful as fungicides being active in tests with *Candida albicans*, *Cryptococcus neoforms*, *Epidermophyton floccosum*, *Blastomyces dermatitidis*, and *Histoplasma capsulatum*.

The compounds are useful in treating the above disorders in humans and in animals such as dogs, cats, cattle, horses, swine, poultry and fur and zoo animals.

The compounds can be used orally in doses ranging

2

from 0.1 mg. to 5 grams daily, depending on the compound and condition under treatment. Parenterally, they can be used in doses ranging between 0.1 mg. and 1 gram daily depending on the compound and condition under treatment. Some irritation may be encountered. For topical use the compounds can be incorporated into creams, ointments or lotions in concentrations of up to 10 percent. Intranasally, e.g., in nose drops and atomizers, the concentration can be in the order of about 0.1 to 2 percent.

The compounds can be used as the free base. Some of the compounds can be isolated and used in the form of their salts with inorganic acids, e.g., hydrochloric or hydrobromic acids, or organic acids such as citric acid, oxalic acid and the like. The compounds can also be isolated and used in the form of their N-oxides and their quaternary salts with quaternizing agents such as lower alkyl sulfates, e.g., methyl sulfates. Such salts are useful for special purposes.

20 The novel compounds of our invention are amino ethers of benzal- and benzyl-carboheterocycles. They can be represented by the following formulas:

(a) The benzal compounds:

(b) the benzyl compounds:

and (c) the benzyl compounds:

40 The AC_nH_{2n}O group is attached to the benzene ring in the meta or para position. A is amino, or alkylamino in which the alkyl group contains from 1 to 4 carbon atoms, or dialkylamino in which the alkyl group contains from 1 to 4 carbon atoms, dibenzylamino, or an N-heterocycle such as morpholino, piperidino, or N-methyl-piperazino and n is 2 or 3. Y is hydrogen or methyl. R is a fluorenylidene, indenylidene, tetrahydronaphthylidene, xanthylidene or thioxanthylidene radical. R' is a fluorenyl, indenyl, tetrahydronaphthyl, xanthyl, thioxanthyl or anthryl radical.

45 Expressed in another way R and R' are

or

65

wherein B represents a bond in R (the benzal compounds), B is hydrogen in R' (the benzyl compounds), and Z is oxygen or sulfur in R and oxygen, sulfur or methylene (CH₂) in R'.

In the benzyl compounds of Formulas b and c, the compounds in which R' is fluorenyl are particularly preferred.

3

The novel benzal compounds can be prepared by four general methods, i.e.,

(1) By the reaction of a hydroxy-benzal compound, substituted with an R group, with a dihaloalkane, e.g., a bromochloro-alkane or a dibromo- or dichloro-alkane, followed by reaction with a suitable amine, i.e.,

(2) By the reaction of the hydroxy-benzal compound of (1) with a haloalkylamino compound, e.g., a dialkyl-aminoalkyl halide or a haloalkylheterocyclic, i.e.,

(3) By the reaction of a benzaldehyde substituted with a $\text{AC}_n\text{H}_{2n}\text{O}$ group with the compound from which R is derived, e.g., fluorene, in the presence of an alkaline catalyst, e.g., sodium methoxide or ethoxide, i.e.,

and

(4) By the reaction of a corresponding acetophenone substituted with a $\text{AC}_n\text{H}_{2n}\text{O}$ group, with a reagent made from butyl lithium and the compound from which R is derived, e.g., fluorene, followed by dehydration, preferably with mineral acids such as hydrochloric, phosphoric or sulfuric acids or acetic anhydride, i.e.,

In the above methods R has the same meaning as in the novel benzal compounds of Formula a described above except that, in method 2, R is not indenylidene, and in method 4 R can be anthrylene. Also, the phenolic starting materials of methods 1 and 2 are preferably used in the form of their alkali metal salts, e.g., sodium, lithium or potassium.

The novel benzyl compounds of Formula c can be generally prepared by method 4.

The novel benzyl compounds of Formula b can be prepared by the hydrogenation, preferably in the presence of a catalyst, e.g., platinum or palladium on charcoal, of the corresponding benzal compounds, i.e.,

The benzyl compounds (b) in which R' is anthryl can be prepared by method 2 using a hydroxy-benzyl-anthracene starting material which can be prepared by method (c) below from anthrone. In method (c) below when anthrone is used a hydroxy-benzyl-anthracene is obtained rather than a hydroxy-benzyl-dihydroanthracene.

The novel benzyl compounds of Formula b or c in

4
which A is amino can also be prepared by the hydrogenolysis of the corresponding benzal compound wherein A is dibenzyl amino.

The hydroxy-benzal intermediates used to prepare the new benzal compounds can be prepared by four general methods, i.e.:

(a) Reacting a compound from which R is derived, e.g., fluorene, with methoxy-benzaldehyde in the presence of a condensing agent such as sodium methoxide or ethoxide or piperidine to form the corresponding methoxy-benzal compound, and demethylating, e.g., with pyridine-HCl, hydrobromic acid or aluminum chloride, to produce the hydroxy-benzal compound, i.e.,

(b) Reacting the R starting compound of (a) with m-hydroxybenzaldehyde, i.e.,

(c) Reacting a ketone containing R with a methoxybenzyl magnesium halide to form the corresponding methoxybenzal compound and demethylating as in method (a), i.e.,

and

(d) Reacting the R starting compounds of (a) with the tetrahydropyranyl ether of hydroxybenzaldehyde, i.e.,

As noted above, an exception to method (c) is the behavior of anthrone (R=anthrylene) which forms benzylmethoxy and benzyl-hydroxy intermediates rather than benzal intermediates, i.e.,

and

This benzyl intermediate can be used in method 2 above to produce the novel benzyl compounds wherein R' is anthryl.

The novel compounds of our invention will be further illustrated by the following examples.

EXAMPLE 1

9-[p-(β -ethylaminoethoxy)benzal]fluorene

A mixture of 735 g. of 9-anisalfluorene and 1070 g. of pyridine hydrochloride was refluxed for 30 minutes, cooled, and the mixture was shaken in water and ether. The ether solution was extracted twice with 10 percent sodium hydroxide solution, this alkaline solution was

rendered acidic with concentrated hydrochloric acid and the residue was taken up into benzene. By reducing the volume of the benzene solution and allowing it to stand at room temperature for prolonged periods, crystals of 9-(p-hydroxybenzal)fluorene were obtained, melting at 110-112° C. This phenol was sufficiently pure for subsequent reactions to form ethers without the need for crystallization. The residue obtained by acidification of the above alkaline solution was either taken up in a known volume of ethanol or dry benzene and aliquot portions used.

A mixture of 82 g. of 9-(p-hydroxybenzal)fluorene and 18 g. of sodium methoxide in 300 ml. of ethanol was stirred for 30 minutes, 180 g. of 1-bromo-2-chloroethane was added and the mixture was refluxed 8 hours. The ethanol and bromochloroethane were removed and a chloroform solution of the residue was washed with 10 percent sodium hydroxide, water, then dried over anhydrous magnesium sulfate. The chloroform was removed and the oily residue, when taken up in ether, settled out as crystals of 9-[p-(β -chloroethoxy)benzal]fluorene, melting at 122-123° C.

A mixture of 89 g. of 9-[p-(β -chloroethoxy)benzal]fluorene and 60 g. of ethylamine in 240 ml. of ethanol was heated in a pressure bottle for 24 hours at 72° C. The excess ethylamine and ethanol were removed and the residue was acidified in ethanol with alcoholic hydrogen chloride. After removing the ethanol and washing the solid with anhydrous ether, the product was triturated three times with hot chloroform, then crystallized from ethanol to give 9-[p-(β -ethylaminoethoxy)benzal]fluorene hydrochloride, melting at 235-236° C.

Analysis.—Calcd. for $C_{24}H_{23}NO \cdot HCl$: C, 76.30; H, 6.40; Cl, 9.38. Found: C, 76.01; H, 6.46; Cl, 9.25.

This compound exhibits the following activities: anti-inflammatory; uterotrophic; produces mouse lung consolidation arrest; antifungal.

EXAMPLE 2

9-[p-(β -dimethylaminoethoxy)benzal]fluorene

A mixture of 30 g. of 9-(p-hydroxybenzal)fluorene and 6.5 g. of sodium methoxide in 150 ml. of ethanol was stirred 30 minutes then was allowed to reflux with a solution of β -dimethylaminoethyl chloride (prepared from 21 g. of the hydrochloride salt) in 150 ml. of toluene for four hours. The solvent was removed, the residue was taken up in ether and after washing twice with 10 percent sodium hydroxide solution and three times with water the ethereal solution was dried over anhydrous magnesium sulfate. After rendering this solution slightly acidic with alcoholic hydrogen chloride and removing the ether, the product was crystallized from methanol-isopropanol to give 9-[p-(β -dimethylaminoethoxy)benzal]fluorene hydrochloride, melting at 217° C.

Analysis.—Calcd. for $C_{24}H_{23}NO \cdot HCl$: C, 76.28; H, 6.40; N, 3.71. Found: C, 75.90; H, 6.41; N, 3.82.

This compound exhibits the following activities: anti-inflammatory; antifungal.

EXAMPLE 3

9-[p-(β -diethylaminoethoxy)benzal]fluorene

When the β -dimethylaminoethyl chloride was replaced with β -diethylaminoethyl chloride in the procedure of Example 2, the hydrochloride salt of 9-[p-(β -diethylaminoethoxy)benzal]fluorene was obtained (from chloroform-ethyl acetate), melting at 196-197° C.

Analysis.—Calcd. for $C_{26}H_{27}NO \cdot HCl$: C, 76.93; H, 6.95; N, 3.45. Found: C, 76.71; H, 7.29; N, 3.38.

This compound can also be prepared by the following procedure:

To 175 ml. of refluxing dihydropyran, containing four drops of concentrated hydrochloric acid, was added 36.6 g. of p-hydroxybenzaldehyde. After refluxing an hour, the excess dihydropyran was removed by distillation at

65

70

75

25 mm. of pressure. One-half of the residue was dissolved in 100 ml. of ethanol and added to a mixture of 16.6 g. of fluorene and 16.6 g. of sodium methoxide in 200 ml. of ethanol. The mixture was refluxed an hour, the solvent was removed and the residue taken up in ether. After washing the ether solution with water, then with saturated aqueous solution of sodium bisulfite, and again with water, 100 ml. of 10 percent hydrochloric acid was added and the ether was allowed to evaporate by heating on a steam bath. An ether extract of the organic layer was extracted with 10 percent sodium hydroxide, the aqueous layer was acidified with 10 percent hydrochloric acid and the precipitated oil was dissolved in ether, washed with water, dried over magnesium sulfate, and the solvent was removed. The residue was 9-(p-hydroxybenzal)fluorene which, when allowed to react (as the sodium salt) with β -diethylaminoethyl chloride, gave 9-[p-(β -diethylaminoethoxy)benzal]fluorene, whose hydrochloride salt was identical with the above.

This compound exhibits the following activities: anti-inflammatory; produces mouse lung consolidation arrest; antifungal.

EXAMPLE 4

9-[m-(β -diethylaminoethoxy)benzal]fluorene

A mixture of 41.5 g. of fluorene and 54 g. of sodium methoxide in 450 ml. of ethanol was warmed to 65° C. and 30.6 g. of m-hydroxybenzaldehyde in 300 ml. of ethanol was added with stirring. After standing at room temperature for 16 hours and then refluxing for 6 hours, the mixture was diluted with an excess of 10 percent hydrochloric acid and extracted with benzene. The organic layer was extracted with 10 percent sodium hydroxide solution, the aqueous layer was acidified and extracted with benzene and the benzene solution was dried over anhydrous magnesium sulfate. The solution was distilled to give 9-(m-hydroxybenzal)fluorene, boiling at 232° at 0.2 mm.

Following the procedure of Example 3, the 9-(m-hydroxybenzal)fluorene (as the sodium salt) was treated with β -diethylaminoethyl chloride to give 9-[m-(β -diethylaminoethoxy)benzal]fluorene whose hydrochloride salt melted at 193-195° C. (from isopropanol).

Analysis.—Calcd. for $C_{26}H_{27}NO \cdot HCl$: C, 76.93; H, 6.95; N, 3.45. Found: C, 76.70; H, 7.17; N, 3.44.

This compound exhibits the following activities: anti-inflammatory; decreases thyroid weight; antifungal; phospholipogenic.

50

45

55

60

70

75

EXAMPLE 5

9-[p-(γ -dimethylaminopropoxy)benzal]fluorene

When the β -dimethylaminoethyl chloride was replaced by γ -dimethylaminopropyl chloride in the procedure of Example 2, the hydrochloride salt of 9-[p-(γ -dimethylaminopropoxy)benzal]fluorene was obtained (from chloroform-isopropanol), melting at 213-214° C.

Analysis.—Calcd. for $C_{25}H_{25}NO \cdot HCl$: C, 76.62; H, 6.69; N, 3.57. Found: C, 76.46; H, 6.84; N, 3.88.

This compound exhibits the following activities: anti-inflammatory; uterotrophic; estrogen antagonist; gonadotrophic inhibitor or androgen antagonist; produces mouse lung consolidation arrest; antifungal.

EXAMPLE 6

9-[p-(γ -diethylaminopropoxy)benzal]fluorene

A mixture of 20 g. of 9-(p-hydroxybenzal)fluorene and 4 g. of sodium methoxide in 150 ml. of dry benzene was refluxed two hours, a solution of γ -diethylaminopropyl chloride (prepared from 22.3 g. of its hydrochloride salt) in 150 ml. of toluene was added and the mixture was stirred and refluxed 16 hours. Following the work-up described in Example 2, the hydrochloride salt of 9-[p-(γ -diethylaminopropoxy)benzal]fluorene was obtained (from isopropanol), melting at 203-204° C.

7

Analysis.—Calcd. for $C_{27}H_{29}NO \cdot HCl$: C, 77.22; H, 7.20; N, 3.34. Found: C, 76.84; H, 7.13; N, 3.55.

This compound exhibits the following activities: anti-inflammatory; antifungal.

EXAMPLE 7

5

9-[*p*-(γ -*dibutylaminoethoxy)benzal]fluorene*

When β -di-*n*-butylaminoethyl chloride replaced the dimethylaminoethyl chloride in the procedure of Example 2, the hydrochloride salt of 9-[*p*-(β -dibutylaminoethoxy)benzal]fluorene was obtained (from isopropanol), melting at 170–171° C.

Analysis.—Calcd. for $C_{30}H_{35}NO \cdot HCl$: C, 78.00; H, 7.86; N, 3.03. Found: C, 77.88; H, 8.07; N, 2.97.

This compound exhibits the following activities: anti-inflammatory; produces mouse lung consolidation arrest.

EXAMPLE 8

15

9-[*p*-(β -*dibenzylaminoethoxy)benzal]fluorene*

A mixture of 33 g. of 9-[*p*-(β -chloroethoxy)benzal]fluorene and 40 g. of dibenzylamine was heated at 160–190° C. for 34 hours, the mixture was triturated several times with benzene and the benzene was removed. The residual oil was triturated with 40–60° petroleum ether three times, the residue was acidified with alcoholic hydrogen chloride and after crystallizing twice from ethanol, the hydrochloride salt of 9-[*p*-(β -dibenzylaminoethoxy)benzal]fluorene was obtained, melting at 180–182° C.

Analysis.—Calcd. for $C_{38}H_{31}NO \cdot HCl$: C, 81.56; H, 6.09; N, 2.64. Found: C, 81.92; H, 5.93; N, 2.64.

This compound exhibits the following activities: uterotrophic.

EXAMPLE 9

20

Alpha-[*p*-(β -*diethylaminoethoxy)phenyl]-alpha-(9-fluorenyl)ethanol*

A solution of butyl lithium (from 2.5 g. of lithium wire and 24.7 g. butyl bromide in 150 ml. dry ether) was added to a solution of 25 g. of fluorene in 150 ml. of dry ether and after stirring 30 minutes, a solution of 35.2 g. of p -(β -diethylaminoethoxy)-acetophenone in 100 ml. of dry ether was added slowly with stirring. The mixture was decomposed with cold water, the ethereal solution was washed repeatedly with water, was dried over anhydrous magnesium sulfate and the solvent was replaced with isopropanol. Crystals of alpha-[*p*-(β -diethylaminoethoxy)phenyl]-alpha-(9-fluorenyl)ethanol were obtained, melting at 104° C.

Analysis.—Calcd. for $C_{27}H_{31}NO_2$: C, 80.76; H, 7.78; N, 3.49. Found: C, 80.86; H, 7.85; N, 3.47.

This compound exhibits the following activities: anti-inflammatory; estrogen antagonist; cholesterol depressant and phospholipogenic; antifungal.

Alpha-[*p*-(β -diethylaminopropoxy)phenyl]-alpha-(1-indenyl)methanol was prepared by the procedure of Example 9 utilizing indene and 4-(α -diethylaminopropoxy)benzaldehyde (prepared from *p*-hydroxybenzaldehyde and α -diethylaminopropyl chloride), which had a boiling point of 142–144° C. (0.5 mm.) The product formed a dihydrogen citrate monohydrate melting at 94° C. with decomposition.

Analysis.—Calcd. for $C_{23}H_{29}NO_2 \cdot C_6H_8O_7 \cdot H_2O$: C, 62.00; H, 7.00; N, 2.50. Found: C, 61.76; H, 6.86; N, 3.02.

EXAMPLE 10

65

9-[alpha-methyl-*p*-(β -diethylaminoethoxy)benzal]fluorene

The ethanol of Example 9 was dehydrated by refluxing in alcohol containing an excess of hydrogen chloride for six hours. Upon cooling, a crystalline product settled out which was recrystallized from ethanol, then dried at 160° C. at 0.5 mm. to give the hydrochloride salt of 9-[alpha-methyl-*p*-(β -diethylaminoethoxy)benzal]fluorene, melting at 221–223° C.

8

Analysis.—Calcd. for $C_{27}H_{29}NO \cdot HCl$: C, 77.20; H, 7.20; N, 3.34. Found: C, 77.18; H, 7.44; N, 3.36.

This compound exhibits the following activities: anti-inflammatory; uterotrophic.

EXAMPLE 11

10

9-[*p*-(β -*piperidinoethoxy)benzal]fluorene*

When the β -dimethylaminoethyl chloride was replaced with N - β -chloroethylpiperidine in the procedure of Example 2, the hydrochloride salt of 9-[*p*-(β -piperidinoethoxy)benzal]fluorene was obtained (for methanol-chloroform) which, after drying at 150° C. at 0.5 mm., melted at 215–216° C.

Analysis.—Calcd. for $C_{27}H_{27}NO \cdot HCl$: C, 77.57; H, 6.75; N, 3.35. Found: C, 77.99; H, 6.27; N, 3.09.

This compound exhibits the following activities: uterotrophic; gonadotropic inhibitor; produces mouse lung consolidation arrest; antifungal.

EXAMPLE 12

15

9-[*p*-(β -*morpholinoethoxy)benzal]fluorene*

When the β -dimethylaminoethyl chloride was replaced with N - β -chloroethylmorpholine in the procedure of Example 2, the hydrochloride salt of 9-[*p*-(β -morpholinoethoxy)benzal]fluorene was obtained (from ethanol), melting at 208–210° C.

Analysis.—Calcd. for $C_{26}H_{25}NO_2 \cdot HCl$: C, 74.36; H, 6.24; N, 3.34. Found: C, 74.24; H, 6.31; N, 3.57.

This compound exhibits the following activities: anti-inflammatory (dextran edema test).

EXAMPLE 13

20

9-[*p*-(β -4-methylpiperazinoethoxy)benzal]fluorene

A mixture of 50 g. of *p*-hydroxybenzaldehyde and 22.4 g. of sodium methoxide in 150 ml. of methanol and 300 ml. of xylene was heated until all the methanol had been removed. A solution of β -4-methylpiperazinoethyl chloride (prepared from 122 g. of the dihydrochloride salt, 69 g. KOH and approximately 75 ml. water) in xylene was added while the sodium salt was being stirred and refluxed. After 16 hours of refluxing, the xylene solution was washed with 10 percent sodium hydroxide, then water and distilled to give 4-(β -4-methylpiperazinoethoxy)benzaldehyde, boiling at 168° C. at 0.2 mm.

A mixture of 12.7 g. of fluorene and 12.9 g. of sodium methoxide in 100 ml. of ethanol was heated with stirring for 30 minutes. A solution of 19 g. of the above benzaldehyde in 100 ml. of ethanol was added and the mixture stood overnight at room temperature. After refluxing an hour, the ethanol was removed, the residue was dissolved in ether and washed with water. The ether solution was then extracted with 10 percent hydrochloric acid, the aqueous layer was rendered basic with 10 percent sodium hydroxide and the oily precipitate was taken up in ether, dried over anhydrous magnesium sulfate and acidified with alcoholic hydrogen chloride. The yellow solid was boiled in ethanol and filtered while hot from the insoluble portion. The filtrate was cooled and the yellow crystals obtained were dried in vacuo at 100° C. The dihydrochloride of 9-[*p*-(β -4-methylpiperazinoethoxy)benzal]fluorene melted at 261–264° C.

Analysis.—Calcd. for $C_{27}H_{28}N_2O \cdot 2HCl$: C, 69.08; H, 6.44; N, 5.97. Found: C, 69.13; H, 6.81; N, 5.70.

EXAMPLE 14

65

9-[*p*-(γ -*piperidinopropoxy)benzal]fluorene*

When γ -piperidinopropyl chloride replaced the β -dimethylaminoethyl chloride in the procedure of Example 2, the hydrochloride salt of 9-[*p*-(γ -piperidinopropoxy)benzal]fluorene was obtained, melting at 246–248° C.

Analysis.—Calcd. for $C_{28}H_{29}NO \cdot HCl$: C, 77.84; H, 7.00; N, 3.24. Found: C, 78.04; H, 7.30; N, 3.21.

This compound exhibits the following activities: anti-inflammatory; antifungal.

EXAMPLE 15

1-[p-(β -diethylaminoethoxy)benzal]indene

A mixture of 13 g. of indene and 6.1 g. of sodium methoxide in 100 ml. of ethanol was refluxed an hour then a solution of 22 g. of 4-(β -diethylaminoethoxy)benzaldehyde in 100 ml. ethanol was added and refluxing was continued for two hours. The alcohol was removed, the residue was taken up in ether, extracted with 10 percent hydrochloric acid, the aqueous layer was rendered basic and extracted with ether. The dried ether solution was acidified with alcoholic hydrogen chloride and the precipitated oil was crystallized from methylene chloride-benzene to give the hydrochloride salt of 1-[p-(β -diethylaminoethoxy)benzal]indene, melting at 197-198° C.

Analysis.—Calcd. for $C_{22}H_{25}NO \cdot HCl$: C, 74.25; H, 7.36; N, 3.94. Found: C, 73.89; H, 7.22; N, 4.07.

This compound exhibits the following activities: anti-inflammatory; gonadotrophic inhibitor or androgen antagonist; decreases thyroid weight; increases adrenal weight; cholesterol depressant.

EXAMPLE 16

1-[p-(β -diethylaminoethoxy)benzal]tetrahydronaphthalene

The Grignard reagent from 102 g. of p-methoxybenzyl chloride in 1400 ml. of ether was added to a solution of 100 g. of alpha-tetralone in 300 ml. of ether and refluxed three hours. After decomposing the mixture with dilute hydrochloric acid, the ether solution was evaporated and the residue was refluxed in alcoholic hydrogen chloride three hours. Crystals of 1-anisaltetrahydronaphthalene separated upon cooling, melting at 86-88° C.

Analysis.—Calcd. for $C_{18}H_{18}O$: C, 86.38; H, 7.25. Found: C, 86.09; H, 7.32.

A mixture of 90 g. of the anisaltetrahydronaphthalene and 168 g. of pyridine hydrochloride was heated at 200° C. for 6 hours. The mixture was taken up in water and ether, the ether layer was extracted with 10 percent sodium hydroxide, the acidified alkaline solution was extracted with ether and the ether was replaced with ethanol-water. Crystals of 1-(p-hydroxybenzal)tetrahydronaphthalene were obtained, melting at 133-135° C.

Analysis.—Calcd. for $C_{17}H_{16}O$: C, 86.40; H, 6.82. Found: C, 86.34; H, 6.89.

When the 9-(p-hydroxybenzal)fluorene was replaced with 1-(p-hydroxybenzal)tetrahydronaphthalene in the procedure of Example 3, 1-[p-(β -diethylaminoethoxy)benzal]tetrahydronaphthalene was obtained as the hydrochloride (from ethanol), melting at 219-221° C.

Analysis.—Calcd. for $C_{23}H_{29}NO \cdot HCl$: C, 74.28; H, 8.13; N, 3.77. Found: C, 74.42; H, 8.25; N, 3.76.

This compound exhibits the following activities: estrogen antagonist.

EXAMPLE 17

9-[p-(β -diethylaminoethoxy)benzal]xanthene

When the alpha-tetralone was replaced with xanthone in the procedure of Example 16, the following intermediates and final product were obtained:

9-(p-methoxybenzal)xanthene (from ethanol-ethyl acetate), melting at 104-107° C.

9-(p-hydroxybenzal)xanthene (from ethanol-ethyl acetate), melting at 181-182° C.

The hydrochloride salt of 9-[p-(β -diethylaminoethoxy)benzal]xanthene (from methanol-isopropanol), melting at 196-197° C.

Analysis.—Calcd. for $C_{26}H_{27}NO_2 \cdot HCl$: C, 74.00; H, 6.69; N, 3.32. Found: C, 73.45; H, 6.78; N, 3.55.

This compound exhibits the following activities: anti-inflammatory.

EXAMPLE 18

9-[p-(β -diethylaminoethoxy)benzal]thioxanthene

When the alpha-tetralone was replaced with thioxanthone in the procedure of Example 16, the following intermediates and final product were obtained:

9-(p-methoxybenzal)thioxanthene (from ethyl acetate-methanol), melting at 134-136° C.

9-(p-hydroxybenzal)thioxanthene (from ether-petroleum ether), melting at 176-177° C.

The hydrochloride salt of 9-[p-(β -diethylaminoethoxy)benzal]thioxanthene (from methanol-isopropanol), melting at 205° C.

Analysis.—Calcd. for $C_{26}H_{27}NO \cdot HCl$: C, 71.28; H, 6.44; N, 3.20. Found: C, 71.06; H, 6.62; N, 3.15; S, 7.32; S, 7.05.

This compound exhibits the following activities: anti-inflammatory: lowers cholesterol/phospholipid ratio; uterotrophic estrogen antagonist.

EXAMPLE 19

9-[p-(β -diethylaminoethoxy)benzyl]anthracene

When the alpha-tetralone was replaced with anthrone in the procedure of Example 16, the following intermediates were obtained:

9-(p-methoxybenzyl)anthracene (from chloroform-ethanol), melting at 138-140° C.

9-(p-hydroxybenzyl)anthracene (from benzene-petroleum ether), melting at 163-169° C.

The final product as the hydrochloride salt was recrystallized from water to give the monohydrate of 9-[p-(β -diethylaminoethoxy)benzyl]anthracene hydrochloride, decomposing at 157-159° C.

Analysis.—Calcd. for $C_{27}H_{29}NO \cdot HCl \cdot H_2O$: C, 74.03; H, 7.36; N, 3.20. Found: C, 74.23; H, 7.59; N, 3.19.

EXAMPLE 20

9-[p-(β -aminoethoxy)benzyl]fluorene

40 A mixture of the free base derived from 22 g. of the hydrochloride of 9-[p-(β -dibenzylaminoethoxy)benzyl]fluorene (Example 8) and 2 g. of 10 percent palladium on charcoal in 200 ml. of ethanol was hydrogenated under 3 atmospheres of hydrogen until the theoretical three molar equivalents of hydrogen had been consumed. After removing the catalyst and acidifying the ethanol solution with hydrogen chloride, the product obtained was recrystallized from chloroform-isopropanol to give the hydrochloride salt of 9-[p-(β -aminoethoxy)benzyl]fluorene,

50 melting at 199° C. (after drying at 140° at 0.5 mm.).
45 *Analysis.*—Calcd. for $C_{22}H_{21}NO \cdot HCl$: C, 75.12; H, 6.31; N, 3.98. Found: C, 75.02; H, 6.61; N, 3.95.

This compound exhibits the following activities: orally active anti-inflammatory; estrogen antagonist; gonadotrophic inhibitor or androgen antagonist; decreases thyroid weight; phospholipogenic.

EXAMPLE 21

9-[p-(β -ethylaminoethoxy)benzyl]fluorene

60 A mixture of 24 g. of the hydrochloride salt of the compound of Example 1 and 3 g. of 10 percent palladium on charcoal in 250 ml. of ethanol was hydrogenated under 3 atmospheres of hydrogen until the uptake of hydrogen ceased. More ethanol was added and the mixture was warmed on a steam bath to dissolve the precipitated amine salt in order to remove the catalyst. After concentrating and cooling the ethanol solution, the hydrochloride salt of 9-[p-(β -ethylaminoethoxy)benzyl]fluorene was obtained, melting at 217-219° C.

Analysis.—Calcd. for $C_{24}H_{25}NO \cdot HCl$: C, 75.90; H, 6.90; N, 3.69. Found: C, 75.64; H, 6.80; N, 3.84.

This compound exhibits the following activities: anti-inflammatory; uterotrophic; gonadotrophic inhibitor; cholesterol depressant.

11

EXAMPLE 22

9-[p-(β -dimethylaminoethoxy)benzyl]fluorene

When the hydrochloride of 9-[p-(β -dimethylaminoethoxy)benzyl]fluorene replaced the substituted fluorene in the procedure of Example 21, the hydrochloride salt of 9-[p-(β -dimethylaminoethoxy)-benzyl]fluorene was obtained, melting at 209-211° C.

Analysis.—Calcd. for $C_{24}H_{25}NO \cdot HCl$: C, 75.90; H, 6.90; N, 3.69. Found: C, 75.48; H, 6.95; N, 4.03.

This compound exhibits the following activities: anti-inflammatory; uterotrophic; gonadotrophic inhibitor or androgen antagonist; phospholipogenic.

EXAMPLE 23

9-[p-(β -diethylaminoethoxy)benzyl]fluorene

When the hydrochloride of 9-[p-(β -diethylaminoethoxy)benzyl]fluorene replaced the substituted fluorene in the procedure of Example 21, the hydrochloride salt of 9-[p-(β -diethylaminoethoxy)benzyl]fluorene was obtained (from isopropanol), melting at 176-178° C. (after drying at 125° C. at 0.5 mm.).

Analysis.—Calcd. for $C_{26}H_{29}NO \cdot HCl$: C, 76.52; H, 7.41; N, 3.43. Found: C, 76.41; H, 7.60; N, 3.54.

This compound exhibits the following activities: anti-inflammatory; uterotrophic; antifungal.

EXAMPLE 24

9-[p-(β -dibutylaminoethoxy)benzyl]fluorene

When the hydrochloride of 9-[p-(β -dibutylaminoethoxy)benzyl]fluorene replaced the substituted fluorene in the procedure of Example 21, the hydrochloride salt of 9-[p-(β -dibutylaminoethoxy)-benzyl]fluorene was obtained (from isopropanol), melting at 156° C.

Analysis.—Calcd. for $C_{30}H_{37}NO \cdot HCl$: C, 77.65; H, 8.25; N, 3.02. Found: C, 77.90; H, 8.31; N, 3.11.

This compound exhibits the following activities: anti-inflammatory; uterotrophic.

EXAMPLE 25

9-[p-(γ -dimethylaminopropoxy)benzyl]fluorene

When the hydrochloride of 9-[p-(γ -dimethylaminopropoxy)benzyl]fluorene replaced the substituted fluorene in the procedure of Example 21, the hydrochloride salt of 9-[p-(γ -dimethylaminopropoxy)benzyl]fluorene was obtained (from isopropanol), melting at 216-217° C.

Analysis.—Calcd. for $C_{25}H_{27}NO \cdot HCl$: C, 76.20; H, 7.16; N, 3.56. Found: C, 75.55; H, 6.99; N, 3.59.

This compound exhibits the following activities: anti-inflammatory; estrogen antagonist; gonadotrophic inhibitor or androgen antagonist; decreases thyroid weight.

EXAMPLE 26

9-[p-(β -piperidinoethoxy)benzyl]fluorene

When the hydrochloride of 9-[p-(β -piperidinoethoxy)-benzyl]fluorene replaced the substituted fluorene in the procedure of Example 21, the hydrochloride salt of 9-[p-(β -piperidinoethoxy)benzyl]fluorene was obtained (from chloroform-isopropanol), melting at 228-230° C.

Analysis.—Calcd. for $C_{27}H_{29}NO \cdot HCl$: C, 77.21; H, 7.20; N, 3.34. Found: C, 76.64; H, 7.17; N, 3.56.

This compound exhibits the following activities: anti-inflammatory; weak uterotrophic.

EXAMPLE 27

9-[p-(β -diethylaminoethoxy)benzyl]fluorene N-oxide

The free base obtained by neutralizing 12 g. of the hydrochloride salt of Example 3 was allowed to react in 200 ml. of methanol with 3.5 ml. of 30 percent hydrogen peroxide for three days. The mixture was stirred with 0.2 g. platinum oxide until oxygen evolution ceased, the catalyst was removed and the solution was concentrated under vacuum below 30° C. Ether was added to the

12

gummy residue whereupon crystals of 9-[p-(β -diethylaminoethoxy)benzyl]fluorene N-oxide, existing as a hydrate, were obtained, decomposing at 111° C.

Anal.—Calcd. for $C_{26}H_{27}NO_2 \cdot H_2O$: C, 77.40; H, 7.25; N, 3.46. Found: C, 77.35; H, 7.42; N, 3.51.

EXAMPLE 28

9-[p-(β -diethylaminoethoxy)benzyl]fluorene methosulfate

The free base from 25 g. of the hydrochloride salt of Example 3 in 200 ml. of dry ether was allowed to react with 8 g. of freshly distilled dimethylsulfate. After standing for three days, the ether was decanted and the residual yellow oil was triturated repeatedly with dry ether. The viscous gum was dissolved in about 100 ml. of methylene chloride and this solution was diluted with 400 ml. of dry ether. The gummy precipitate was allowed to stand under dry ether for two days whereupon solidification of the entire mass finally was effected. The solid was dissolved in a minimum of ethanol and this solution was diluted with butanone and a little dry ether. Crystals of the methosulfate of 9-[p-(β -diethylaminoethoxy)benzyl]fluorene were obtained, melting at 179-180° C.

Anal.—Calcd. for $C_{26}H_{27}NO \cdot (CH_3)_2SO_4$: C, 67.86; H, 6.71. Found: C, 67.34; H, 6.70, N, 2.83, N, 2.89.

The compounds of the above examples exhibited the activities described for each (except anti-fungal activity and blood cholesterol and phospholipogenic activity) when administered parenterally (subcutaneously). Also, the compound of Example 20 exhibited anti-inflammatory activity and the compounds of Examples 3, 7 and 11 produced mouse lung consolidation arrest when administered orally. The compounds of Examples 4, 9, 15, 18, 20, 21 and 22 exhibited blood cholesterol or phospholipogenic activity when administered orally. The tests were carried out on mice and rats. Anti-fungal activity was determined in vitro with the fungi described above.

The following examples illustrate suitable pharmaceutical preparations containing the new compounds. In these examples, the quantities are given for single units, it being understood that in actual practice, the dosage forms will be prepared in suitable quantities, and the amounts of materials used adjusted accordingly.

EXAMPLE 29

25 MG. TABLETS

Twenty-five mg. of the hydrochloride of 9-[p-(β -diethylaminoethoxy)benzyl]fluorene (Example 3), 48 mg. of powdered sugar, and 32 mg. of corn starch are mixed and granulated with 10 percent gelatin solution. The granulation is dried and ground to fine granules for tableting. About 1 percent magnesium stearate is added as a lubricant, together with sufficient corn starch to give a weight of 2.5 grains per tablet. The product is compressed on a single punch or rotary machine using a $\frac{1}{32}$ inch punch.

EXAMPLE 30

500 MG. TABLETS

Five hundred mg. of the hydrochloride of 9-[p-(β -diethylaminoethoxy)benzyl]fluorene (Example 3) in finely powdered form is admixed with 60 mg. of corn starch and 100 mg. of powdered sugar and then granulated with 10 percent gelatin solution. The granulation is dried and ground to size suitable for tableting. About 1 percent magnesium stearate is added as a lubricant, together with sufficient corn starch to give a weight of 700 mg. per tablet. The product is compressed on a single punch or rotary machine using a $\frac{1}{16}$ inch punch.

The tablets of Example 29 and Example 30 may be suitably coated if desired, as, for example, with sugar.

EXAMPLE 31
CAPSULE

Twenty-five mg. of the hydrochloride of 1-[p-(β -diethylaminoethoxy)benzyl]indene (Example 15) is admixed with corn starch in quantity required to provide sufficient bulk for the desired size capsule, and the mixture is encapsulated.

EXAMPLE 32
CAPSULE

Five hundred mg. of the hydrochloride of 9-[p-(β -aminoethoxy)-benzyl]fluorene (Example 20) is admixed with sufficient corn starch to give the proper bulk for the desired size capsule, and the mixture is encapsulated.

EXAMPLE 33

INJECTABLE SUSPENSION, 100 MG. PER ML.

The following ingredients are sterilized separately: 100 mg. of the hydrochloride of 9-[p-(β -diethylaminoethoxy)benzyl]fluorene (Example 3), 0.1 mg. of Tween 80 and q.s. corn oil to make a final volume of 1 ml. These ingredients are admixed aseptically. Particle size may be achieved by use of micronized material or by use of a ball mill, maintaining aseptic conditions. The above suspension may be administered subcutaneously and intramuscularly.

EXAMPLE 34

LIQUID (SYRUP) 25 MG. PER TEASPOON

Twenty-five mg. of the hydrochloride of 1-[p-(β -diethylaminoethoxy)benzyl]indene (Example 15) is dissolved in 1 ml. of water. Five mg. of sodium benzoate, 3.5 ml. of liquid sugar, 5 mg. of citric acid, and 0.375 mg. of butoben are added and stirred until dissolved, using gentle heat if necessary. Flavor, as desired, and water q.s. are then added.

EXAMPLE 35

LIQUID (SYRUP) 500 MG. PER TABLESPOON

Five hundred mg. of the hydrochloride of 9-[p-(β -diethylaminoethoxy)benzyl]fluorene (Example 3) and 4.5 mg. of sugar are dissolved in sufficient water so that after the addition of 2.25 ml. of alcohol USP and flavor, as desired, the volume is 15 ml.

EXAMPLE 36

INJECTABLE SOLUTION 100 MG. PER ML.

One hundred mg. of the hydrochloride of 9-[p-(β -diethylaminoethoxy)benzyl]fluorene (Example 3) and water for injection q.s. 1 ml. are mixed and warmed gently till solution is accomplished. The solution is filtered through fine sintered glass, filled into sterile 1 ml. ampuls, and sterilized at 250° F. for 30 minutes.

EXAMPLE 37

1% OINTMENT

To a melt of 1.5 lbs. of propylene glycol 6.68 lbs. of polyethylene glycol 400 USP and 6.68 lbs. of carbowax 4000 USP is added 0.15 lb. of micropulverized hydrochloride of 9-[p-(β -aminoethoxy)benzyl]fluorene (Example 20). The product is stirred until almost solid and milled if necessary to a smooth ointment. Fill in suitable containers.

EXAMPLE 38

10% OINTMENT

To a melt of 1.5 lbs. of propylene glycol, 6 lbs. of polyethylene glycol 400 USP and 6 lbs. carbowax 4000 USP is added 1.5 lbs. of micropulverized hydrochloride of 1-[p-(β -aminoethoxy)benzyl]fluorene (Example 20). The product is stirred until almost solid and milled if necessary to a smooth ointment. Fill in suitable containers.

EXAMPLE 39
ISOTONIC SOLUTION, 0.25%

A mixture of 0.25 g. of the hydrochloride of 9-[p-(β -diethylaminoethoxy)benzyl]fluorene (Example 3), 0.026 g. of methylparaben, 0.014 g. of propylparaben, 0.875 g. of sodium chloride, and 90 ml. of distilled water is stirred until a clear solution is obtained. Distilled water is added to make a final volume of 100 ml. The solution is put in suitable containers for dispensing as nose drops, for atomizing, or for use in aerosol sprays.

EXAMPLE 40

ISOTONIC SOLUTION, 2%

15 A mixture of 2.0 g. of the hydrochloride of 9-[alpha-(β -diethylaminoethoxy)benzyl]fluorene (Example 3), 0.026 g. of methylparaben, 0.014 g. of propylparaben, 0.613 g. of sodium chloride, and 90 ml. of distilled water is stirred until a clear solution is obtained. Distilled water is added to bring the final volume to 100 ml. The solution is put in suitable containers for dispensing as nose drops, for atomizing, or for use in aerosol sprays.

EXAMPLE 41

AEROSOL SPRAY, AQUEOUS

25 Solutions from Examples 39 or 40 may be placed into a pressurized container, pressurized with nitrogen, helium or a mixture of both, so that the initial head pressure is in the range of 65-75 pounds per square inch, and 30 atomized through "micro-mist" valves (available from Precision Valve Company).

Such a solution may also be metered through a number of different aerosol valves to give a solution weight of from 25 mg. to 250 mg. per charge. (Such metered 35 valves are available from Rison Valve Company or Aerosol Techniques, Inc.). Container size may be selected from any of the many available containers commercially available, varying in size from 10 ml. to 8 ounces and made from glass, nylon, aluminum or coated 40 tin plate.

EXAMPLE 42

FREON PROPELLED AEROSOL

Twenty grams of the hydrochloride of 9-[p-(β -aminoethoxy)benzyl]fluorene (Example 20) is dissolved in 45 water, and 100 ml. 5 percent sodium hydroxide solution is added. The water insoluble oily base is extracted with ether; the ether extract is dried over anhydrous magnesium sulfate and evaporated on the steam bath and finally in a vacuum desiccator. One gram of the residual oily free base is dissolved in a mixture of 80 g. of Freon 114 and 20 g. of Freon 12 in the cold (-20° C. or lower). The solution is "cold filled" into an appropriate pressure container. Such a container may have a gauge pressure of 18-25 pounds per square inch at normal room 55 temperature and can be dispensed from a metered valve.

We claim:

1. Compounds of the formula selected from the group consisting of

and

wherein the $AC_nH_{2n}O$ group is attached to the benzene ring in one of the positions meta and para; A is selected 75 from the group consisting of amino, alkylamino in which

15

the alkyl group contains from 1 to 4 carbon atoms, di-alkylamino in which the alkyl group contains from 1 to 4 carbon atoms, dibenzylamino, morpholino, piperidino, and N-methylpiperazino groups; n is an integer of 2 to 3; Y is selected from the group consisting of hydrogen and methyl; wherein R is selected from the group consisting of fluorenylidene, indenylidene, tetrahydronaphthylidene, xanthylidene and thioxanthylidene radicals and wherein R' is selected from the group consisting of

16

fluorenyl, indenyl, tetrahydronaphthyl, xanthyl, thioxanthyl and anthryl radicals.

2. 9-[p-(β -diethylaminoethoxy)benzal]fluorene.
3. 9-[m-(β -diethylaminoethoxy)benzal]fluorene.
4. 9-[p-(β -piperidinoethoxy)benzal]fluorene.
5. 1-[p-(β -diethylaminoethoxy)benzal]indene.
6. 9-[p-(β -aminoethoxy)benzyl]fluorene.
